UNITED STATES PATENT OFFICE.

LEWIS Y. MYERS, OF CANTON, OHIO.

HAY-CARRIER.

SPECIFICATION forming part of Letters Patent No. 276,864, dated May 1, 1883.

Application filed November 4, 1882. (No model.)

To all whom it may concern:

Be it known that I, LEWIS Y. MYERS, a citizen of the United States, residing at Canton, in the county of Stark and State of Ohio, have 5 invented certain new and useful Improvements in Hay-Carriers, of which the following is a specification, reference being had therein to the accompanying drawings.

This invention relates to a hay-carrier of the 10 class illustrated in my previous Patent No. 243,600, dated June 28, 1881; said carrier being arranged to move back and forth upon a suspended rod, rail, or track, and being provided with automatic latches and stops, by 15 which the loaded fork is at the proper moment locked in position upon the carrier and loosened therefrom. In my said patent a construction of carrier is shown in which the loaded fork is suspended from and supported by the 20 sliding latch, while the carrier is moved back and forth upon the track. This method of supporting the load is, under some circumstances, inferior; and one of the purposes of the present invention is to provide a means of 25 supporting the load directly upon the main frame of the carrier.

The invention also relates to other matters, which will be hereinafter described in detail.

Figure 1 is a side view of a carrier embodying my improved features. Fig. 2 is a side view, with one side piece of the frame removed to show the inner parts, the catch being locked.

A represents a rod, rail, or other suitable track, suspended in any preferred way above 35 the place where it is desired to deposit the hay, and adapted to have the carrier move thereon.

The carrier is constructed with some features similar to those shown in the aforesaid 40 patent; but in order to set forth clearly the improvements which I have made I will briefly describe all the parts of the device herein shown.

The main frame consists of one or more 45 pieces, B, there being, preferably, two of the same, which are best arranged when substantially parallel, there being suitable cross connecting and tying pieces. The frame, however, may be more or less modified without de- 50 parting materially from the essential parts of the invention. Preferably it is suspended upon

two wheels or anti-friction rollers, b', situated so as to support the frame to best advantage.

c is a pulley or sheave over which, ordinarily, the hoisting-rope is passed. Over this pulley it runs to the hoisting-fork at C', which is supported loosely upon the rope, preferably by means of a pulley having an upwardly-projecting swivel or eye-piece, C². The rope is fastened at the end by means of an eye, C³.

The main frame is constructed with a hook, ledge, or shoulder, B', adapted to engage with the swivel or eye C², and when it is supported thereon the frame operates to hold the load that is being carried. With this ledge, shoul- 60

der, or supporting device on the main frame I combine means for so guiding the swivel or eye that when it is being raised it shall come into proximity with said ledge, hook, shoul- 65

der, or supporting device, and in the construc- 70

tion shown said guiding devices are so con- 75

structed and arranged that the eye or swivel is brought to a point somewhat above the horizontal line or supporting ledge or shoul- 80

der. The guides consist of curved edges b. 75

With these parts I also combine an automatic- 85

ally-acting part, which can be caused to hold the carriage stationary while the load is ris- 90

ing, which, secondly, can be rocked so as to release the carriage after the load has been se- 80

cured in place on the latter, which, thirdly, can be caused to release the fork-holder from the ledge or notch on the main frame, and which can also assist in securing the fork- 95

holder upon said ledge or notch. As shown, 85

this part which performs or assists in perform- 90

ing these functions consists of a bar, plate, or lever, C, arranged to automatically engage 95

with a stop, i, by which stop it holds the car- 90

riage in position until the load has been ele- 95

vated, and by which it operates to release the 100

fork-holder from the carriage or main frame. This part C is supported in such manner that the end which engages with the stop i can be oscillated or swung up and down, the other end being arranged to be moved up by the fork-support when the latter is rising. This part C is secured in place by one or more pins, as at h h', which provide a support for it more or less pivotal, about which the ends of the part C can oscillate sufficiently for the purpose required. In the form of construction which

- I have shown the part C not only has the oscillating motion above described, but also more or less of a longitudinal movement. To allow this movement, the apertures through which the pin or pins h h' pass are elongated and curved or made angular, as at x x' . The lever C is also provided with downwardly-extended projections, shoulders, pins, lugs, or hooks f f' , or equivalent devices. The projection f' is so related to the other parts that when the lever C strikes against the stop i it (said part f') presses against the eye or bail of the fork-holder and throws it off from the supporting ledge or notch on the main frame.
- 15 In addition to the projection f' , there is a projection or shoulder, f , which can be used to assist in guiding the fork-holder into proper position above the support or notch on the main frame, and when the lever C is caused to move longitudinally (as it does in the construction shown) said part f can be caused (while going through its oscillating and sliding movement) to give a positive pull, if necessary, upon the eye or bail of the fork-support. This part f need not be of exactly the form shown—that is to say, the operative edge thereof may be more or less inclined relatively to the other parts without materially affecting its operations.
- 20 The lever C is, at the outer end, notched or recessed, as at g^2 , one of the walls g^4 being adapted to engage with the outer side of the stop i , and provide a positive lock for the carriage. Said part C has also an inclined face 25 or projection, g , which, by impinging against the stop i , is adapted to cause the projection or shoulder f' to disengage the eye or bail of the fork-support from the main frame. The stop i is adjustable upon the rod, rail, or track, 30 so that the carrier can be stopped at any desired point.
- 25 C^4 is an eye in the lever C, by means of which a rope is connected therewith, the rope running back over a pulley and carrying a weight which operates to return the carrier after the fork has been unloaded. This weight also insures that the carrier shall be held properly when stationary, and assists in holding the lever C in proper position relatively to the fork-support while the carrier is being moved. 40 However, the weight may be dispensed with, and the rope may be operated by hand, if desired.
- 30 The operation of the device is as follows: The fork is first loaded with hay, and then a lifting action is exerted upon the rope e . This raises the fork-support (the eye or bail C^2 and its pulley) until it reaches the guiding devices at b , which compel the fork-support to come 45 into proximity to the support on the main frame, (the notch, shoulder, or ledge.) After the fork-holder has got above the notch or shoulder it will move over the same, owing to the fact that the eye or bail C^2 , to which the rope is 50 attached, is lower than the pulley E; or, if the lateral movement of the fork-support does not

result from this, the end of the lever C will operate to guide said eye or bail into proper position above the notch or shoulder at B' . While the eye or bail of the fork-support is rising it lifts up the end of the lever C, and correspondingly lowers the outer end, which is engaged with the stop i . I prefer, for some reasons, not to have this dropping of the end of the part C so great as to entirely disengage it at first, (though that can be done, if desired) but rather wish to have a part of it remain in engagement for an instant longer, in order that it may pull the lever C slightly longitudinally. When constructed and operating thus, 80 as soon as the pin h' reaches the vertical part of the slot x' the outer end of lever C makes a second dropping or swinging movement, bringing it far enough down to escape from stop i ; but I do not wish to be limited to 85 the exact form or movement in detail of this part of the machine. When a longitudinal movement of the lever C is thus employed the part f can be caused to pull the eye or bail of the fork-support over the shoulder or notch at 90 B' . This latter operation, however, is not essential, as the eye or bail of the fork-support will, under ordinary circumstances, automatically pass into position to rest upon the shoulder or notch.

95 It will be seen that the parts are so related that after the carriage begins to move away with its load the eye or bail cannot escape readily from the shoulder or notch on the main frame, as it is surrounded by a wall of metal 100 formed partly by the main frame, and partly by the lever C, and the latter can be held down to its place by the weight and cord attached to the eye C^4 . The load is carried to the desired point and dropped, after which the carrier is returned by means of the rope and weight, or otherwise, until the part g strikes the stop i , whereupon a movement, partially oscillating and partially sliding, is given to the lever C, which compels the shoulder or projection f' to lift or push the fork-holder off from the support on the main frame, so that the fork can drop for another load.

105 I do not wish to be limited to the exact form of the support upon the main frame, (represented at B') nor to the rising and falling fork-holder C^2 , nor to the exact shape of the parts g g' , nor to the means of fastening the lever C, as these parts may be varied somewhat and yet retain the features of my invention.

110 120 What I claim is—

1. In a hay-carrier, the combination of a rising and falling fork-holder, a sliding main frame provided with a support for the fork-holder, the movable projection or shoulder f' , 125 and means, substantially as described, for automatically causing said projection or shoulder to release the fork-holder from the support on the main frame.

2. In a hay-carrier, the combination of a rising and falling fork-holder, the main frame provided with a support for the fork-holder, a stop

secured to the rail or track, and a lever carried by the main frame, and which is adapted to have its outer end engage with said stop, and to have said end swing downwardly relatively to said stop when the rising fork-holder strikes the other end, substantially as set forth.

3. In a hay-carrier, the combination of a rising and falling fork-holder, the main frame provided with a support for the fork-holder, the lever constructed to form an inclosing-wall or closed eye around the bail of the fork-holder, and adapted to have attached to it a rope and weight, substantially as set forth.

4. In a hay-carrier, the combination of a rising and falling fork-holder, the main frame provided with a support for the fork-holder, and with a rounded or curved wall adjacent to said support for guiding the rising fork-holder into proximity to its support and the means for lifting the fork-holder, substantially as set forth.

5. In a hay-carrier, the combination of a rising and falling fork-holder, the main frame provided with a support for the fork-holder, the means for lifting the fork-holder, the means for automatically releasing the fork-holder from the support on the main frame, and the guide which directs the fork-holder into proximity to its support on the main frame, substantially as described.

6. In a hay-carrier, the combination of a rising and falling fork-holder, the main frame provided with a support for the fork-holder, the rope for lifting the fork-holder, the guide which directs the fork-holder into proximity to its support on the main frame, the releasing bar or plate C, provided with a projection or shoulder for engaging with the fork-holder, and means, substantially as described, for causing said projection or shoulder to bear against the fork-holder and release it from its support on the main frame, substantially as described.

7. In a hay-carrier, the combination of a rising and falling fork-holder, a sliding main frame provided with the shoulder or ledge for supporting the fork-holder, the hoisting-rope, the fork-pulley having an eye or swivel to engage with said shoulder on the main frame, the guide which, while the pulley eye or swivel is rising, guides it into proximity to said shoulder or ledge, the movable bar or plate C, the means which automatically move said bar or plate C, and the means for engaging it with the pulley eye or swivel, substantially as set forth.

8. In a hay-carrier, the combination of a rising and falling fork-holder, a sliding main frame provided with a support for the fork-

holder, the movable hook or shoulder f, adapted to engage with the fork-holder, and means, substantially as described, for automatically causing said hook or shoulder f to engage with the fork-holder and move it toward the support on the main frame, substantially as set forth.

9. In a hay-carrier, the combination of a rising and falling fork-holder, a sliding main frame provided with a support for the fork-holder, the plate or bar C, provided with projection or shoulder f' for releasing the fork-holder and provided with the shoulders or projections g g' and the stop i, substantially as set forth.

10. In a hay-carrier, the combination of the rising and falling fork-holder, the main frame provided with a support for the fork-holder, the stop i, the bar or plate C, supported upon the main frame by a pin or pins which permit it to oscillate, the means carried by said bar or plate C for engaging with and releasing the fork-holder, and the projections or shoulders g g', adapted to strike against the stop i and produce a vibrating of the bar or plate C, substantially as set forth.

11. In a hay-carrier, the combination of a rising and falling fork-holder, the sliding main frame provided with a support for the fork-holder, the stop i, the bar or plate C, having the projection g and the eye or rope-fastening device C' to receive a returning rope, substantially as set forth.

12. The combination of the main frame, the rising and falling fork-holder, and the lifting-rope connected to the frame at two points—one lower than the other—to assist the fork-holder in moving longitudinally relatively to the main frame toward its support on said frame, substantially as set forth.

13. In a hay-carrier, the combination of a rising and falling fork-holder, the main frame provided with a support for the fork-holder, the stop upon the rail or track, and a catch-lever having a notch at its outer end to engage with the said stop to hold the main frame stationary, and provided with a projection which engages with said stop prior to the engagement of the notch therewith, for the purpose of producing said engagement between the notch and stop.

In testimony whereof I affix my signature in presence of two witnesses.

LEWIS Y. MYERS.
